MULTIPLE TRANSFORMER ARRANGEMENT

Application filed March 16, 1927. Serial No. 175,655.

This invention relates to arrangement of high potential transformers developing voltages substantially equal to the combined voltages of the several transformers, and has for one object, the provision of a transformer hook-up which will produce a voltage substantially equal to the sum of the voltages of the several transformers without impairing the regulation of the transformers, and, at the same time, producing a combination having a possible power output substantially equal to the sum of the outputs of the individual transformers. Other objects and advantages will appear from the following description and claims. The invention is exemplified in the combination and arrangement of parts shown in the accompanying drawings and described in the following specification, and it is more particularly pointed out in the appended claims.

In the drawings—

Fig. 1 is a diagrammatic view illustrating one embodiment of the present invention.

Fig. 2 is a view similar to Fig. 1 showing a slightly different arrangement.

Fig. 3 is a diagrammatic view showing the arrangement especially adapted to power transmission lines.

Fig. 4 is a view similar to Fig. 3 showing a slightly different arrangement.

In transformers, particularly those used for the generation of high voltages, there are several important considerations to be taken into account. One is to build a suitable transformer which will provide sufficient reliability for very high voltage without excessive cost. This is particularly true when the voltages are exceedingly high. A further consideration is to secure good regulation, that is ratio of voltage at full load to that at no load. A still further consideration is the power or k. v. a. output of the transformer or combination of transformers. A still further consideration is the provision of a suitable arrangement of transformers and apparatus, so that the required high voltage and power output may be obtained without damage to the transformer.

One of the most effective ways in protecting a transformer, particularly one used un-

der the severe conditions of high voltage testing, is to insert a resistance in series with the high voltage winding. This resistance must be of a fairly high value, as a comparatively small current in the high voltage winding 55 may set up very severe conditions within the transformer winding. It is therefore necessary that a comparatively high resistance be used so that it will tend to absorb any disturbance tending to damage the transformer.

With the ordinary concatenated or chain connection, where a few end turns of one transformer are used to excite the next transformer in the chain or series, it is exceedingly difficult or practically impossible to provide resistance protection. This is due to the fact that the few turns must carry a large current as compared to that produced by the load in the high tension winding. If a resistance were inserted in these leads which have to carry the heavy exciting current, much energy would be absorbed and the regulation of the transformer chain would be very poor.

In order to improve the regulation and power or k. v. a. output and at the same time provide suitable protection to the transformers, I have devised a new scheme or arrangement for a combination of transformers. One such arrangement is shown in Fig. 1. Suitable transformers, A, B and C are provided with high tension windings 10, 11 and 12, and primary or low tension windings 13, 14 and 15, the transformers being energized by alternators 16, 17 and 18.

In the arrangement shown in Fig. 1, the center point of the high voltage winding in each transformer is grounded on the case. This usually results in the cheapest type of transformer for a given voltage. It is evident, however, that any other point might be grounded or the end of the winding grounded on the case. When one end of the high voltage winding is grounded on the case, generator 16 may be mounted at any convenient point and need not be insulated from ground. Where the center point of the transformer is grounded, it is usually advisable to mount the

generator on the transformer tank or on a suitable insulated base.

Where the generators are insulated, it is necessary to drive the generators by a suitably insulated shaft 38 or belt 37. Where 5 the high voltage windings are arranged in chain connection, the several generators may be driven by belts or by induction motors, the slip in the belt or induction motor providing the necessary distribution of the load among 10 the several generators, as the chain connection will tend to maintain the proper phase relation.

In the ordinary chain or concatenated connection, the amount of power or k. v. a. output 15 is limited to that of the smallest or most highly worked transformer in the chain. If, therefore, three transformers of the same size were connected in series or in chain formation, the total k. v. a. output would be that 20 of a single transformer only, whereas with my improved connection, the k. v. a. output would be the total of all the transformers, or three times the amount. This in itself is a 25 very great advantage, particularly where it is desired to keep down the cost of the transformers for a given output or where it is desired to obtain a large output, as in the case of power work.

In Fig. 1 the connections between the points 30 19 and 20, or 21 and 22, will have little or no current except that produced by the load, or that required to keep the several transformers in proper phase relation. Since the 35 amount of current produced by the load at very high voltage is exceedingly small, and the current flowing between the two transformers is very small compared to that in the ordinary chain connection, the end or exciting turns between the points 21 and 19 and 22 and 20, may have much smaller current carrying capacity than in the case of the ordinary concatenated or chain form. This results in a considerable saving.

Since the current flowing in the conductors 40 between the two transformers is comparatively small, it is possible to insert comparatively high resistances, 31, in all of the leads connecting the transformers together, as well as to the load and to ground. The fact that these 45 resistances may be of appreciable magnitude, makes it possible to absorb the energy in small currents which might otherwise cause destruction or a breakdown in the insulation of the transformer. This is particularly true in 50 testing conditions where the transformer windings are likely to be impressed with very severe voltages set up by high voltage discharges.

Once the transformers and generators are 55 in proper phase relation, a slight load on the series will usually tend to maintain proper phase relation. It is evident that where the 60 load or current flowing through the high voltage winding of the transformers will

maintain them in synchronism, the chain or concatenated connection may be dispensed with and the transformers operated in a direct series. Where the core and case of one or more of the transformers are insulated from 70 ground and connected to the high tension windings, as in Fig. 1, the core and case form with the ground a condenser which receives its charging current from the high tension winding, thus placing sufficient capacitance 75 load on the transformers to hold the several units in step after they have once been synchronized even though there is no other load on the transformers. The concatenated arrangement can be used to facilitate starting 80 up, and phasing of the transformers. After this, the exciting connection between the transformers may be dispensed with and a direct connection between the end turns of adjacent transformers established as between 85 19 and 22, 23 and 26. In order to do this, a suitable disconnecting switch, 32 and 33, must be opened and connection made at 34.

It is evident that this arrangement may be established in a variety of ways. By using 90 a suitable reactance 35 in one of the circuits, the connection 34 can be established before switch 32 or 33 are opened. After switches 32 and 33 are opened and 34 is closed, the full voltage of each transformer is added to the 95 next, which gives a somewhat higher voltage than where the concatenated or chain arrangement is used. The casing and core of the various transformers is diagrammatically represented at 36.

Where suitable drives are provided to control the speed of the several generators, either by driving through synchronized motors attached by shafts, or by manual speed control using various speeds in the driving motors, 100 or by automatic speed control so that the various transformers are given the proper phase relation, it is apparent that the ordinary concatenated or exciting winding is unnecessary, even for starting up. This arrangement is 105 shown in Fig. 2.

In Fig. 2 the transformers D, E and F are connected through resistances 40 and 41, and to the ground and load by resistances 42 and 43. It is evident that either the center or one end of the high voltage winding may be grounded on the case, as desired, or to conform with the apparatus which is desired to connect up. It is also evident that part of the 110 transformers might be grounded at one end on the case, and part grounded at the center on the case, without materially affecting the arrangement. While the resistances may vary considerably with the apparatus one quarter of an ohm to an ohm per volt generated can be used, without appreciable effect upon the regulation, and this will afford material protection to the transformer against steep wave fronts or high frequency 115 disturbances in the insulation.

Where the centers of transformers D, E and F are connected to the respective cases, it is necessary to insulate the transformers and exciting generators in accordance with the voltage to ground. The arrangement shown in Fig. 2 gives the full accumulated voltage of all of the transformers and the full k. v. a. output. Where the transformers are of equal size, the k. v. output will be three times that of the chain connection and the voltage regulation will be as good for the series as for a single transformer. The improved regulation and power output are of considerable value in determining test results for high voltage research work. The multiple excitation with insulated generators is a decided advantage over the chain excitation in that the power output of the several transformers is accumulated and not limited to the smaller transformer or the very highly loaded one in the chain.

The highest voltage in the transformer winding with respect to ground, may be electrically connected to the case rather than the low side. Where the connection is made up in this way, the large surface of the transformer case can be utilized to reduce the concentration of stress in the air and further act as a condenser for supplying additional energy for high voltage or impact tests. The case and core of the transformers are represented diagrammatically in each instance at 45.

The method can be used to advantage for raising the voltage and increasing the power output or for regulating the voltage for transformer work. With the scheme as outlined, it is, of course, necessary to insulate the generator from ground for the voltage generated by the succeeding transformer or transformers. For power work, it is, of course, necessary to provide an insulated coupling of suitable size for transmitting the power from the prime mover to the generator, but even where the voltage is comparatively high, this need not be a serious factor.

An arrangement suitable for a transmission line is shown in Fig. 3, which illustrates one phase of a polyphase system. In this figure, G represents the first transformer in the series and H the boosting or regulating transformer in the series. The high voltage winding 50 of the first transformer has one end connecting to ground or to the neutral. The low voltage winding 51 is connected to one phase of the generators. The high voltage winding is provided with suitable end turns 52 which are connected with suitable end turns 53 of the high voltage winding 54 of transformer H, or if desired, the leads from the end turns 52 may be connected to the low voltage winding 55 of transformer H, this winding being arranged in series with the winding 54 providing, of course, that the voltages generated are suit-

able. This arrangement makes it possible to use the old transformers on a system greatly increasing the power output and at the same time maintains the good regulation which would normally be much poorer with the second transformer operated entirely as an auto transformer from the first. The connection between the end turns of the transformers G and H will keep the two transformers in phase.

If the insulated generator 56 of transformer H is not driven, it will act as a motor and could be used in this connection at the receiving end for either taking off power or the control of voltage.

The generator connected to transformer H is of course, a single phase generator insulated from the ground. The exciter for this generator is of necessity insulated from ground. Even where the first transformers energize a 110 k. v. transmission line, the provision of insulation for the transformers and the construction of a suitable insulating coupling for the generator, even for larger amounts of power, is not a serious problem. The reason for this is that the margin of insulation required at the low side of the high tension winding, as compared to the side connected to the line, need not be very high, as line surges produced by lightning, switching or grounds are damped out by the high voltage winding, and while these voltages are very high on the side line, the rise in voltage on the low side of the winding will be comparatively slight under operating conditions. A 110 k.v. transmission system has approximately 65,000 volts to ground. The surges coming in from the transmission line may be exceedingly high, running to several hundred-thousand volts and in some cases, probably exceeding a million volts. If the insulated generator were subjected to this voltage, the insulated coupling would necessarily have to be exceedingly large to provide a sufficient factor of safety so that the arrangement would not be practicable.

With the arrangement shown in Fig. 3 however, the transformer H will absorb the very high voltages so that the generator and insulated coupling will have to provide only a reasonable margin of safety for the 65,000 volts normally imposed upon the coupling and generator.

Where it is possible to drive the insulated generator 56 and the generator energizing the winding 51 of transformer G from the same prime mover, it is unnecessary to provide the auto transformer connection between transformer G and transformer H. The arrangement being practically that shown in Fig. 2 with the exception that the resistance 40 would be omitted, this arrangement has the advantage that special transformers are not required and old transformers may be used as part of the chain.

It, of course, is evident that synchronizing of the transformers, secured by driving the generators for the different primary windings from a common prime mover 60, in which case the synchronizing connection between the end turns 52 and 53 may be omitted. This general arrangement is shown in Fig. 4, in which the secondary windings 57 and 58 are directly connected in series. 10 This arrangement takes advantage of the fact that transformer I will not be subjected to excessive high voltages, since it is protected from line surges by the interposed winding 58, permitting the transformer to be 15 designed on a much lower margin for insulation. This tends to permit a transformer to have better efficiency, lower cost and better regulation.

A computation showing the relative regulation of the ordinary concatenated or chain arrangement of transformers as compared to the present invention, shows the value of the latter where close regulation is desired for transmissions or testing. A given series 20 of three transformers using the ordinary chain connection has an estimated regulation of 32 percent in going from full load leading current to full load lagging current. The same series of transformers with the improved multiple excitation under the same 25 load conditions, has an estimated regulation or change in voltage of 1.28 percent only. The improved connection has the same regulation of 1.28 percent for a series of four 30 transformers, while the same four transformers with the ordinary chain connection has an estimated regulation of 53 percent for the same changes in load.

I claim:

40 1. In combination, a plurality of transformers having their high potential windings connected in series, means for separately exciting the low potential windings of two of said transformers, said exciting means being energized from a source other than the windings of said transformers to avoid high current values in said transformer windings and a resistance in series with the high potential windings of said transformers of sufficient value to be effective in materially 45 reducing surges in said windings.

50 2. In combination, a plurality of transformers having their high potential windings in series, alternators for energizing the low potential windings of two of said transformers, the alternator for the transformer having the higher potential position in said series being insulated from the earth and a resistance interposed in series with the high potential windings of said transformers.

55 3. In combination, a plurality of transformers having their high potential windings connected in series, generators for separately energizing the low potential windings

of two of said transformers, the generator for the transformer having the higher potential position in said series being insulated from the earth and resistance interposed in series with said high potential windings, the minimum amount of said resistance being approximately one-quarter of one ohm per volt generated by said secondary windings. 70

4. In combination, a plurality of transformers having end turns of the high potential winding of one connected in parallel with end turns of the high potential winding of another, to assist in maintaining synchronism between said transformers, alternators for separately energizing the low potential windings of said transformers and resistance interposed in the connections between said end turns. 75

5. In combination, a plurality of transformers, an end turn at the high potential end of the high potential winding of one of said transformers being connected in parallel with an end turn at the low potential end of the high potential winding of another of said transformers, alternators for separately energizing the low potential windings of said transformers and switches for changing the connection between said high potential windings to place all of the turns of said high potential windings in series. 80

6. In combination, a plurality of transformers having turns of their high potential windings connected in parallel to assist in maintaining synchronism between said transformers, means for separately energizing the low potential windings of said transformers, resistance interposed in the connections between said high potential windings and switches for changing the connection between said high potential windings to place all of the turns thereof in series. 100

7. In combination, a plurality of transformers having their high potential windings arranged in series with end turns of adjacent transformers in said series connected in parallel, means for separately energizing the low potential windings to said transformers and means for changing the connections between the high potential windings of said transformers to place all of the high potential windings of said transformers in series. 110

8. In combination, a plurality of transformers having their high potential windings arranged in series and having end turns of the high potential windings of adjacent transformers connected in parallel, resistances interposed in the connections between said high potential windings, means for separately energizing the low potential windings of said transformers, switches for changing the connections between said high potential windings to place all of the turns of said high potential windings in series and inductive resistance arranged in series with certain 120

115

125

130

of said switches to prevent surges when said switches are operated.

9. In combination, a pair of transformers having their high potential windings arranged in series and connected to a transmission line, means for separately energizing the low potential windings of said transformers, the high potential winding of the transformer having the higher potential position in said series, being interposed between the line and said means for energizing the low potential windings of said transformers to protect said energizing means from surges in the transmission line.

10. In combination, a pair of transformers having their high potential windings connected in series and connected to a transmission line, the transformer next adjacent said transmission line being provided with a higher degree of insulation than the other of said transformers to withstand the effect of surges in said transmission line, and means for separately energizing the low potential windings of said transformers, said energizing means for the transformer having the higher potential position in said series being insulated from the earth and protected from surges in said line by the high potential windings connected with said line.

11. In combination a plurality of transformers having their high tension windings connected in series, one end of the series of high tension windings being grounded, each transformer having its high tension winding connected to the core and case of the transformer, a separate alternator electrically connected with the low tension winding of each of said transformers and resistance in series with said high tension windings, the alternators for the transformers having higher potential positions in said series having their frames insulated from ground.

12. In combination a plurality of transformers having their high tension windings connected in series, independently driven means for exciting the low tension windings of said transformers, and means connected with said high tension windings for subjecting said windings to a capacitance load for maintaining said transformers and their driving means in step.

13. In combination a plurality of transformers having their high tension windings connected in series one point in the high tension circuit thus formed being grounded, independently driven excitors for exciting the low tension windings of said transformers, and means connected with said high tension circuit at a point removed from the grounded point thereof for subjecting said high tension circuit to a capacitance load.

14. In combination a plurality of transformers having their high tension windings connected in series, one end of the series circuit thus formed being grounded, indepen-

dently driven excitors for exciting the low tension windings of said transformers, the case of one of said transformers being insulated from ground, said insulated case being connected with the high tension circuit of said transformers at a point removed from the grounded end of said circuit to subject said high tension circuit to a capacitance load.

In testimony whereof I have signed my name to this specification on this 12th day of March A. D. 1927.
